(57) **CLAIM**

The ornamental design for fastener belt, as shown and described.

DESCRIPTION

FIG. 1 is a perspective view of fastener belt showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The fastener belt is shown broken away at its center in the figure views in order to indicate that a specific length of fastener belt forms no part of the claimed design.
